Attorney

UNITED STATES PATENT OFFICE.

VIRGIL LEONARD WOODS, OF WILLIAMS, CALIFORNIA.

FOUNTAIN BRUSH.

Application filed July 19, 1922. Serial No. 576,062.

To all whom it may concern:

Be it known that I, VIRGIL L. Woods, a citizen of the United States, residing at Williams, in the county of Colusa and State of California, have invented certain new and useful Improvements in Fountain Brushes, of which the following is a specification, reference being had to the accompanying drawings.

10 This invention relates to fountain brushes, and more particularly to fountain shaving brushes.

An object of the invention is to provide a brush of this character composed of a 15 few number of parts which may be readily disassembled or removed and replaced by new parts.

It is another object of the invention to provide a brush of this character including 20 a container from which a flexible nozzle extends into the brush head, the nozzle being capable of movement with the bristles of the brush.

It is a further object of the invention 25 to provide a device of this character wherein the container is provided with a valve mechanism adapted to stop or control the supply of material from the container without interfering with the movement of the 30 nozzle disposed within the brush head.

With these and other objects in view, the invention consists in the improved construction and arrangement of parts to be hereinafter more particularly described, 35 fully claimed and illustrated in the accompanying drawings, in which:—

Figure 1 is a longitudinal sectional view of a fountain shaving brush constructed in accordance with an embodiment of the invention;

Figure 2 is a sectional view taken on the line 2—2 of Figure 1; and

Figure 3 is a perspective view of the plate and valve cage.

Referring to the drawings, 5 designates a container which serves as the handle member of the brush, the walls of the container being of a shape to fit the hand of the user. The end 6 of the container is open and 50 provided with interior threads 7 adapted to be engaged by the exterior threaded flange of a cover 8. The central portion of the cover is provided with a threaded opening 9, the purpose of which will be hereinafter described. Depending from the

cover 8 centrally thereof, and concentric to the opening 9, is a sleeve or valve casing 10. The casing extends longitudinally of the container, and terminates inwardly of the opposite end 11 of the container. The end 60 12 of the valve casing is interiorly threaded for a purpose to be hereinafter described.

The end 11 of the container is open for the reception of a plate 13, said plate being concavo-convex and having its peripheral 65 edge formed into a flange adapted to engage the end face of the end 11 of the container. The plate 13 has a central opening 14 adapted to receive a cone valve cage 15, the apex portion of the cone projecting 70 beyond the end of the container. The upper end portion 16 of the cone is exteriorly threaded and adapted to be threaded into the end portion 12 of the valve casing. The cone valve cage may be secured to the 75 edge of the opening 14 in any suitable manner to provide a smooth and unobstructed surface at the junction of the cone valve cage. The cone valve cage 15 is provided with a series of inlet openings 17, said openings being disposed closely adjacent the connection of the cone valve cage with the plate 13 so as to permit discharge of all of the 80 contents of the receptacle and eliminate waste. These openings may be made as 85 large or as small as desired, or any number desired, according to the size of the brush.

Disposed in the valve casing 10 is a valve stem 18 provided on one end with an operating knob 19 and having its upper end portion 20 threaded for engagement with the threads of the opening 9 of the cover and by means of which the stem is raised and lowered relative to the valve casing. The opposite end of the valve stem is provided 95 with a threaded socket 21 adapted to receive a threaded plug 22, the major portion of the plug being crimped and adapted to be inserted into a flexible valve 23, said valve being made preferably of soft rubber, 100 and of a size to frictionally engage the cone valve cage. The valve 23 is normally disposed in the cone valve cage and is intended to close the openings 17 or to regulate the flow of the matter from the container. 105

In connection with the container, a brush head 24 is provided, said brush head having bristles secured thereto by any suitable means, the upper end of the brush head being concave to conform to the convex por- 110

tion of the plate 13, the central portion of the brush head having an opening 25 adapted to receive a nozzle 26.

The nozzle 26 is preferably made of pliable rubber and includes an annular flange 27 adapted to engage the concave portion of the brush head, the nozzle extending through the opening 25 into the bristles of the brush, said nozzle tapering from the flange to the end thereof, while the handle of the nozzle is the same diameter at all points longitudinally thereof. In view of the fact that the nozzle is pliable, it may be moved in any direction with the movement of the bristles of the brush, and at the same time it is also disposed to supply the bristles with matter from the container.

When the cone valve 15 is threaded into the valve casing 10, it causes the flange of the plate 13 to frictionally engage the end of the container, thereby preventing leakage of the contents between the plate 13 and the container. To permit relative movement of the plate and brush head, the concave face of the plate 13 is provided with lugs 28 adapted to extend into the brush head. The container may be supplied with liquid soap, or like toilet preparation by removing the cover 8. The soap surrounds the valve casing 10. Discharge of the soap from the container is through the opening 17 and into the nozzle 25, the discharge of the soap being controlled by the pliable valve 23 through the medium of the knob 19 which may be rotated to raise or lower the valve. When the valve is closed the flexibility of the valve 23 permits the same to be forced into the cone portion of the cage so as to positively obstruct all of the openings. At the same time, in view of the fact that the cone is made of metal, the wedging action of the valve within the cage does not dilate the nozzle 25. The apex portion of the cage, of course, extends into the nozzle, so as to prevent leakage of the contents between the flange of the nozzle and the brush head. The brush head is provided with a flange 29 which is interiorly threaded and projects above the concave top of the brush head, said flange being arranged to engage the exteriorly threaded end 11 of the container, the flange 11 being simultaneously engaged with the container upon movement of the cone valve cage with the casing 10.

From the foregoing it will be readily seen that this invention provides a novel form of shaving brush capable of receiving a large quantity of matter, such as liquid soap, and wherein the soap is not directly discharged into the brush from the container but passes through the cone valve into and through the flexible nozzle, so that waste is prevented. An important fea-

ture of this device is that the openings in the cone valve cage are disposed closely adjacent the opening in the plate 13 so that every drop of liquid in the container may be discharged into the nozzle 25. Furthermore, in case the brush should be placed upon its end face, or in other words, should the cover 8 be used as a base to support the brush in its inverted position, the pliable valve will prevent passage of liquid soap through the casing 10. All of these features are possessed by a device composed of a few number of simple parts.

What is claimed is:

1. A fountain brush of the character described comprising a tubular handle open at its opposite ends and having a removable cover at one end and a brush head at the opposite end, the brush head including a flexible nozzle extending into the bristles of the brush, a tubular member attached to the cover and removable therewith and extending into the handle to a position adjacent to the base of the nozzle, a conical member disposed in the base of the nozzle and projecting into the handle with which said tubular member is adapted to have screw-threaded engagement, the conical member having openings to afford communication between the nozzle and the interior of the handle, and a valve inserted through said cover and disposed within the tubular member and adapted to be forced into the conical member to close the openings thereof.

2. A fountain brush comprising a tubular handle having a removable cover, a tubular casing attached to the center of the cover, the cover having a central opening for the reception of a valve stem, said valve stem being disposed within the valve casing, a brush head having a conduit therethrough, a valve plate disposed on the inner face of the head and provided with a perforation to register with the conduit, a valve cage rigid with said plate and discharging through the plate into the brush conduit, the valve cage being formed with radial openings communicating with the interior of the handle, said valve stem carrying a valve adapted to close said openings when the valve stem is shifted inward.

3. A fountain brush comprising a tubular handle having a removable cover, a brush head having detachable engagement with the end of the handle opposite the cover and having bristles, the brush head being provided with a conduit therethrough, the inner end of the conduit carrying a hollow member projecting into the interior of the handle and exteriorly screw-threaded, said member inward of the head being perforated, a tube mounted upon the cover and extending into the handle and having screw-threaded engagement with said member, and a valve normally disposed within the member and

having a stem extending out through the tube and cover, and the cover and casing having screw-threaded engagement with the latter whereby the valve may be forced into 5 the conical member to close the apertures thereof or withdrawn therefrom.

4. In a fountain brush, a hollow handle, a brush head detachably engaged with said handle, a nozzle of flexible rubber extending 10 through the brush head and having a base on its inner end, the brush head being re-

cessed to receive said base, a plate extending over the base and engaged with said brush head, and a valve disposed within the handle and operative to close or open the passage 15 through the nozzle whereby to control the flow of liquid through said nozzle, and means exterior to the handle to operate said valve.

In testimony whereof I hereunto affix my signature.

VIRGIL LEONARD WOODS.
